Attest

United States Patent Office.

SAMUEL SEMPLE, JR., OF MOUNT HOLLY, NEW JERSEY.

Letters Patent No. 100,675, dated March 8, 1870.

IMPROVEMENT IN STOP-MOTION FOR SPOOLING-MACHINES.

The Schedule referred to in these Letters Patent and making part of the same.

To all whom it may concern:

Be it known that I, SAMUEL SEMPLE, Jr., of Mount Holly, in the county of Burlington, and in the State of New Jersey, have invented certain new and useful Improvements in Cop-Spool Machines; and do hereby declare that the following is a full, clear, and exact description thereof, reference being had to the accompanying drawings and to the letters of reference marked thereon making a part of this specification.

The nature of my invention consists in the construction and arrangement of a "cop-spooling machine," for doubling three or more strands of yarn or thread off cops of yarn or bobbins on to one bobbin.

In order to enable others skilled in the art to which my invention appertains to make and use the same, I will now proceed to describe its construction and operation, referring to the annexed drawings, in which—

Figure 1 is a side elevation, part in section, of my machine, and

Figure 2 is a plan view of the same.

A represents the bed-piece of my machine, at one end of which are two standards, B B, having between them at their upper ends a round felt or cloth-covered bar, C.

On the rear or outer side of the bar C, are placed a number of wire guides, a a.

Under this bar the cops D D, from off which the yarn or thread is to be taken, are placed.

At the other end of the bed A is a frame, E, through which passes an upright shaft, G, provided with a pulley, H, to be connected with an engine or machinery, for the purpose of revolving the shaft.

Upon the upper end of the shaft G is placed the bobbin or spool I, on which the doubled yarn or thread is to be wound.

At a suitable distance above its lower end on the shaft G, is securely fastened a collar with two horizontal arms, J J, for a purpose that will be hereinafter described.

On the bed-plate A, between the frames B C and E, is a small metal frame, K, in which are pivoted a number of drop-wires, b b, which pass through a slotted upright guide-plate, L, and are then bent upward, and their upper ends forming hooks, c c.

Under the wires b b in the frame K, is pivoted a lever, nearly balanced.

One end, M, of this lever is T-shaped, as shown in fig. 2, and extends under the wires b b nearly to the guide-plate L, while the other end, N, extends to near the shaft G, and has at its outer end a wing or plate, O, as shown in fig. 1, this being so arranged that when the lever M N is balanced, or nearly so, the plate O will be below the arms J J on the shaft G, and not interfere with the revolution of said shaft.

The strands of yarn or thread are taken from the cops D D below and passed through the wire guides a a, over the bar C, and thence through the hooks c c of the drop-wires b b to the bobbin I.

Before reaching the bobbin I, the strands pass over a guide-wire, d, extending from the frame E, so as to guide them onto the bobbin.

By this arrangement the drop-wires b b are raised to the height of the slots in the guide-plate L, as shown in fig. 1, and the plate-lever M N is nearly balanced.

When either strand of yarn breaks, the weight of the drop-wire is sufficient to lower the T-shaped arm M, raising the arm N, so that the arm J on the shaft or spindle G is caught by the plate O, causing it to stop, thereby arresting the motion of the bobbin I, and preventing less than the proper number of strands passing on to the bobbin.

It will be seen that the strands of yarn are kept separate until they are nearly on the bobbin, thus getting an exactly uniform tension on each thread, which is of the first importance in securing a good, evenly-twisted thread.

Having thus fully described my invention,

What I claim as new, and desire to secure by Letters Patent, is—

The arrangement within the standards B B and frame E, of bar C, with wires a a, spindle G, with pulley H and arms J J, frame K, drop-wires b b, guide-plate L, lever M N, stop O, and guide d, all constructed and operating as and for the purposes herein set forth.

In testimony that I claim the foregoing I have hereunto set my hand this 12th day of January, 1870.

SAMUEL SEMPLE, JR.
